UNITED STATES PATENT OFFICE.

ROBERT SCHEY, OF NEW YORK, N. Y., ASSIGNOR TO MAX KAUFMANN & CO. INC., OF NEW YORK, N. Y., A CORPORATION OF NEW YORK.

DESIGN FOR A TEXTILE FABRIC.

Application filed December 21, 1925. Serial No. 15,813. Term of patent 3½ years.

To all whom it may concern:

Be it known that I, ROBERT SCHEY, a citizen of the United States, and a resident of the city of New York, borough of Manhattan, in the county and State of New York, have invented a new, original, and ornamental Design for Textile Fabrics, of which the following is a specification, reference being had to the accompanying drawing, forming a part thereof, wherein—

The essentials of the design comprise a trellis-like effect upon a contrasting ground interspersed with clusters of conventionalized flowers.

The figure is a plan view of a textile fabric showing my new design.

What I claim, and desire to secure by Letters Patent, is:

The ornamental design for a textile fabric as shown and described.

ROBERT SCHEY.
